COMPRESSED AIR BLOW GUN

James T. Clark, Fort Morgan, Colo.

Filed Apr. 30, 1964, Ser. No. 79,749

Term of patent 14 years

(Cl. D62—2)

FIG. 1

FIG. 2

FIG. 1 is a side elevational view of a compressed air blow gun showing my new design and

FIG. 2 is a front elevational view thereof.

The side opposite that in FIG. 1 is a mirror image of the side shown in FIG. 1.

I claim:

The ornamental design for a compressed air blow gun, as shown and described.
